UNITED STATES PATENT OFFICE.

HARRY BENJAMIN BOTTNEN, OF MARSHALLTOWN, IOWA.

WIRE-SPlicer.

1,111,639.

Specification of Letters Patent. Patented Sept. 22, 1914.

Application filed March 31, 1914. Serial No. 828,490.

To all whom it may concern:

Be it known that I, HARRY B. BOTTNEN, a citizen of the United States, and a resident of Marshalltown, in the county of Marshall and State of Iowa, have made certain new and useful Improvements in Wire-Splacers, of which the following is a specification.

My invention is an improvement in wire splicers, and has for its object to provide a device of the character specified, especially adapted for use in weaving fences of wire, or in any other condition where it is desired to twist two wires together, wherein a twisting mechanism is provided for engaging the wires, so arranged that one wire will be held firmly while the other is twisted around the same, and wherein means is provided for automatically locking the first-named wire in position operated by the insertion of the wire.

In the drawings; Figure 1 is a side view of the improved splicer with parts in section, Fig. 2 is a longitudinal section, Fig. 3 is a partial side view looking at the opposite side from Fig. 1, and Fig. 4 is a section on the line 4—4 of Fig. 3 looking in the direction of the arrows adjacent to the line.

The present embodiment of the invention consists of sections 1 and 1^a adapted to be superposed and secured together, to form a handle or grip and a species of casing for holding the splicing mechanism. The section 1^a is provided on its inner face with a longitudinally extending rib 2 which is designed to fit within a similarly shaped groove 3 in the section 1, and screws 4 and 5 are provided for securing the sections together, the screws passing transversely of the sections, and having their heads countersunk in the section 1, as indicated at 6.

Each of the sections 1 and 1^a is provided at one end with an arc-shaped extension 7 and 7^a respectively, and each of the extensions is grooved on its inner face longitudinally of the extension, as indicated at 8 and 8^a respectively. A rotatable approximately cylindrical head 9 is arranged between the extensions 7 and 7^a, the said head having an annular external rib 10, which is received within the grooves 8 and 8^a before mentioned, to prevent longitudinal movement of the head with respect to the extensions.

The head is provided with a central opening 11, and with a radial slot 12 extending from the opening, and adapted to register

with a passage 13 which is left between the adjacent ends of the extensions 7 and 7^a. The said extensions are spaced apart at the end remote from the handle to limit the said passage 13. The rib 10 before mentioned is provided with a series of ratchet teeth 14 on its periphery, as shown in Fig. 1, and a pawl 15 is pivoted in a recess between the sections, and at the junction of the extensions with the bodies of the sections for coöperating with the teeth.

The pawl is pivoted at 16, and a coil spring 17 normally presses the pawl toward the teeth. One end of the spring engages the pawl, and the other end is seated in a recess 18 in the section 1^a. At one side of the slot 12 the head is provided with a pair of jaws 19 and 20, each of the said jaws having its inner face perpendicular to the adjacent end of the head, and its outer face inclined, as shown, and the perpendicular faces of the jaws are spaced apart from each other, as shown in Fig. 2.

The inner face of the jaw 19 is notched or recessed, as shown at 19^a adjacent to the end of the head. A circular plate or disk 21 is connected with the opposite end of the head from the jaws, the plate being pivoted to the head by means of a screw 22, which passes through an opening in the plate or disk and engages a registering internally threaded opening in the adjacent end of the head. The head of the screw is of relatively large size, and engages outside of the plate, as shown in Fig. 2. This guard plate is provided with a radial lug 23 for engagement by the finger of the operator, to move the same, and the plate is also provided with a lug 24 extending inwardly over the periphery of the head, to limit the swinging movement in one direction, to a position where its periphery registers with the periphery of the head. The plate is also provided with another inwardly extending lug 25 directly opposite the lug 24, and a coil spring 26 has one end connected with the lug 25, the other end being secured to the head, and the spring is arranged within the recess 27 in the head. The spring normally acts to hold the plate in register with the head, and to return the plate to such position when it is displaced by means of the finger piece or lug 23.

The plate is provided with a central opening 28 registering with the opening of the head, and with a curved or arc-shaped slot

or passage 29 leading from the opening 28 to the periphery of the plate. The slot or passage 29 is so arranged that it is never in complete register with the slot 12 of the head. One wall of the slot normally stands in inclined position across the slot 12, and it will be evident that when the head is so arranged that the passage 12 thereof is in alinement with the passage 13 between the 10 extensions 7 and 7^a, the said wall 30 of the slot 29 will stand in inclined position across the slot 12 of the head.

The inclined edge 30 of the slot acts as a cam, so that when a wire is passed through 15 the passage 13 and the slot 12 of the head, it will engage the inclined face 30 of the slot 29, and will swing the plate to permit the wire to enter the central opening 11 of the head, and the central opening 28 of 20 the plate.

The lug 25 of the plate moves into the recess 27 of the head when the head is so swung, compressing the spring 26, and as soon as the wire enters the central opening 25 of the head and plate, the spring will swing the plate to original position, thus closing the inner end of the passage or slot 12.

The operation of the device is as follows: With the parts in the position of Figs. 1, 2 30 and 3 the line wire is introduced into the central opening 11 of the head. The splice wire is engaged between the jaws 19 and 20, and the handle formed by the sections 1 and 1^a is oscillated around the line wire. When 35 the handle is so operated the splice wire will be twisted around the line wire, the said splice wire slipping down into the notch or recess 19^a, which prevents its disengagement from the jaws. If it is desired 40 to release the instrument from the line wire, it is only necessary to swing the plate 21 in the proper direction. The central opening 11 of the head, as also the central opening 28 of the plate, is of sufficient diameter 45 to permit the line wire to move freely through the opening, regardless of small kinks and twists. The pawl and ratchet connection between the head and the handle permits free reverse rotation of the handle 50 with respect to the head, but so long as the handle is kept moving forwardly, the splice wire will be twisted around the line wire. It is not necessary to swing the handle completely around the line wire, but merely to 55 oscillate the same. When the handle is moved in a direction to twist the splice wire, the pawl and ratchet connection between the handle and the head causes the head to move forward with the handle, while the handle 60 may be moved freely in the reverse direction.

I claim:—

1. A wire twister comprising a handle having at one end a substantially circular 65 casing provided with a central opening and

with a radial slot leading from the opening, a head journaled in the opening and provided with a central opening and with a radial slot leading from the opening and adapted to register with the slot of the casing, a pawl and ratchet connection between the head and the casing for constraining the head to move with the handle when the handle is moved in one direction, and for permitting the handle to move freely with respect to the head when the handle is moved in the other direction, the head having a pair of spaced jaws extending from one face, a guard plate pivoted to the opposite end of the head from the jaws for permitting the entrance of a wire to the opening of the head and for preventing displacement thereof, and a spring normally holding the guard plate in position to prevent displacement of the wire. 85

2. A wire twister comprising a handle provided at one end with a transverse opening, a head mounted to rotate in the opening, a pawl and ratchet connection between the head and the casing for constraining the head to move with the handle when the handle is moved in one direction, the head having a central opening and a radial slot leading from the opening, and the handle having a passage with which the slot is 90 adapted to register, said head having jaws extending longitudinally therefrom at one end, a guard plate pivoted to the other end for permitting the entrance of a wire to the central opening and for preventing displacement thereof, and a spring normally holding the guard plate in position to prevent displacement of the wire. 95

3. A wire twister comprising a handle provided at one end with a transverse opening, a head journaled for rotation in the opening and having a central opening and a radial slot leading from the opening, the handle having a slot with which the slot of the head is adapted to register, the head having a pair of spaced jaws at one end for gripping the splice wire, and a guard plate pivoted to the opposite end of the head for permitting the entrance of the line wire to the central opening and for preventing disengagement therefrom, said plate comprising a disk having a central opening adapted to register with the opening of the head, and having an inclined slot, and means for normally holding the plate with one wall of the slot across the slot of the head, and a pawl and ratchet connection between the head and the handle. 110 115

4. A wire twister comprising a handle provided at one end with a transverse opening, a head journaled for rotation in the opening and having a central opening and a radial slot leading from the opening, the handle having a slot with which the slot of the head is adapted to register, the head hav- 125 130

ing a pair of spaced jaws at one end for gripping the splice wire, and a guard plate pivoted to the opposite end of the head for permitting the entrance of the line wire to the central opening and for preventing disengagement therefrom, said plate comprising a disk having a central opening adapted to register with the opening of the head, and having an inclined slot, and means for normally holding the plate with one wall of the slot across the slot of the head.

5. A wire twister comprising a handle and a head journaled at one end of the handle

for rotation, said head having a central opening and a radial slot leading from the 15 opening for receiving the wire and having a pair of jaws at one side of the opening for engaging the wire, and a guard plate normally closing the inner end of the radial slot of the head and movable to permit the 20 entrance or exit of the wire.
